COMBINED WASTE CAN, LID, AND ENCLOSURE

Filed Dec. 15, 1949

UNITED STATES PATENT OFFICE

2,621,099

COMBINED WASTE CAN, LID,
AND ENCLOSURE

Roger Lehman, Orange, N. J.

Application December 15, 1949, Serial No. 133,194

5 Claims. (Cl. 312—273)

1

This invention relates to new and useful improvements in a storage structure for garbage cans and similar waste receptacles.

More particularly the present invention proposed improvements in odor-proof and sanitary storage structures for garbage cans and other waste receptacles characterized by a cabinet incorporating a main housing, a slide-out drawer within which such can may be temporarily stored while resting on the bottom wall of the drawer, a cover for the can permanently movably mounted in said housing, a pull-out handle or equivalent for the drawer, and means operable in timed relation to movements of the drawer relative to the housing and in such manner that when the drawer is fully inserted in the housing said cover is lowered down tight on top of the can and also in such manner that incidental to a movement of the drawer outwardly of the housing said cover is raised in the housing and out of engagement with the top of the can thereby to facilitate easy outward slide of the drawer.

As will be understood, the outward sliding of the drawer will ordinarily be effected for moving the front limit of the can to a location beyond the front end of the roof wall of the cabinet merely to a sufficient extent to permit garbage or other refuse to be conveniently dropped into the can by way of its open top; while at less frequent intervals the drawer will be slid outwardly to the full extent required to permit lifting of the can upwardly out of the cabinet for suitable disposal of its waste contents.

A feature of the invention is the general simplicity and compactness of the entirety of the new combination, including, especially, the now preferred nature of the can-cover raising and lowering means; said means preferably mainly incorporating merely two like straight levers each having a field of swing in a plane closely adjacent to a different one of the two side walls of the housing.

A further object of the present invention proposes several methods of slidably supporting the drawer within the housing so that the drawer may be freely pulled outward when it is desired to place something within the garbage can or remove the same for the purpose of emptying its contents.

The new storage structure may have its cabinet of generally rectangular shape, and be so constructed, as of thin sheet metal, and so finished, for example by being enamelled white, as to provide not only a useful addition to a kitchen, pantry or the like, but also a decorative such addition as well.

It is still another object of the present invention to construct a storage structure for garbage cans or other similar waste receptacles which is simple and durable and which can be manufactured and sold at a reasonable cost.

For further comprehension of the invention, and of the objects and advantages thereof, refer-

2

ence will be had to the following description and accompanying drawings, and to the appended claims in which the various novel features of the invention are more particularly set forth.

5 In the accompanying drawings forming a material part of this disclosure:

Fig. 1 is a perspective view of the storage structure for garbage cans or other waste receptacles constructed in accordance with the present invention.

10 Fig. 2 is a vertical sectional view taken substantially on the line 2—2 of Fig. 1.

Fig. 3 is an enlarged partial vertical sectional view taken on the line 3—3 of Fig. 2.

15 Fig. 4 is a horizontal sectional view taken on the line 4—4 of Fig. 2.

Fig. 5 is an enlarged perspective view of the front end of one of the tracks used in the form of the invention shown in Figs. 1 to 4.

20 Fig. 6 is a view similar to Fig. 3, but illustrating a modification of the present invention.

The storage structure for garbage cans and other similar waste receptacles, according to the form of the invention shown in Figs. 1 to 5, includes a housing 10 having a top wall 11, a back wall 12 and a pair of side walls 14; said housing being wholly open at its front and also open at its bottom. The housing 10 is reinforced by a brace 15 extended between the bottom front corners of the side walls 14, see Figs. 2 and 3.

25 Within the housing 10 there is a drawer 16 comprising a bottom wall 17 and a front wall 18. The drawer's bottom wall 17, along its opposite sides, is supported for horizontal travel, by a guide structure incorporating a pair of like tracks 19 each at the inner side of a different one of the two side walls 14. Each of the tracks 19 includes, as best shown in Figs. 2 and 3, a channel strip suitably secured to the adjacent side wall 14 by a rivet 20 relative to the back wall 12 and a bent-over extended portion 21 of the central web of the strip and by a rivet 22 relative to the adjacent side wall 14.

30 As just stated, the tracks 19 are alike; but, as will be understood, with the direction of bend of the web portion 21 of the strip 19 extended as shown in Fig. 2, the bend of the corresponding portion of the other strip will be in the opposite direction, so that the grooves of the two tracks 19 35 parallelly face each other in the same horizontal plane.

35 Said guide structure includes, for coaction with the tracks 19, not only a floating cylindrical rod 24, but also a pair of like rollers 26, see Figs. 2 and 3. The rollers 26 are engaged in the tracks 19 on opposite sides of the interior of the housing 10 and rotatably mounted on the ends of a cross- 40 axle 27.

45 The axle 27 is suspended horizontally and in proper position by way of a pair of like straps 31 depending from the drawer's bottom wall 17; which latter has an upstanding rear flange 30 50 as shown. Each of the straps 31 is secured at

its upper end portion by rivets 32, to the flange 30. With the straps 31 spaced about equally inward from the side walls 14, each has its lower end portion curled for embracing the axle 27. For retaining the axle 27 against rotation, the rod is secured to the straps 31 by pins 33 which also retain the axle 27 against axial movement relative to the straps 31. From Fig. 3 it will be noted that the straps 31 are positioned in close proximity to the rollers 26 so as to retain the rollers against undesirable axial movement on the cross-axle 27 and in position within the tracks 19.

The ends of the cylindrical rod 24 rest on the top faces of the tracks 19 with the bottom face of the bottom wall 17 of the drawer 16 resting on top of the rod. Means is provided for restricting the rod 24 to an area of operation which is normally beneath the front portion of the bottom wall 17 of the drawer, when the drawer 16 is completely pushed into the housing 10, as shown in full lines in Fig. 2. The restricting means comprises a pair of spaced lugs 29, see particularly Figs. 2, 3 and 5, which projects upward from each of the tracks 19 and on opposite sides of the rod 24. Thus, the lugs 29 act to restrain the rod 24 from rolling too far to the back of the tracks 19, when the drawer 16 is being pushed inward, and from rolling off the front ends of the tracks, when the drawer 16 is being pulled outward, and so provide an adequate support for the front portion of the bottom wall 17 of the drawer 16.

The can is conventionally shown at 34. The can cover is illustrated as in the form of a rectangular plate 35 carrying a pair of like upstanding slotted extensions 36 at its rear edge and a pair of like depending apertured ears 37 at its front edge.

The can cover 35 is of such width that, as will be noted from Fig. 4, the ears 37, widthwise of the drawer 16, are spaced so as to be beyond the lateral limits of the can 34 with the latter resting by its own weight on the drawer's bottom wall 17.

To each of the two depending ears 37 at the forward end of the cover 35 adjacent to the front of the housing 10, the upper slotted end of a different one of the two like forwardly upwardly inclined levers 38 is pivotally connected by a pin 39. By means of the slotted extensions 36 upstanding from the cover 35 at its rear edge, the rear edge of the cover 35 is given a pin and slot mounting within the housing 10, by pins 40 applied as shown relative to spacing blocks 41 and the two side walls 14 of the housing.

The lower end of each lever 38 is pivotally connected to a different one of two forwardly bent end portions 30^a of the flange 30 by a pin 42, see Figs. 2 and 3.

The two pin and slot connections participating in the permanent mounting of the cover 35 within the housing 10 insure that the cover, with the drawer 16 fully inserted as shown in full lines in Fig. 2, will always settle squarely and tightly on the open top of the can 34, even should the latter, in the size fabricated for a cabinet of predetermined capacity, have a height variation from that intended.

The drawer 16 has projected forwardly of its front wall 18 a handle 43 fixed on said wall.

The operation of the storage structure is as follows:

By simply pulling on the handle 43, the drawer 16 may be partially withdrawn from the housing 10, to the extent desired. If such with-

drawal is merely to obtain access to the top of the can 34 to permit easy addition of refuse thereto, the pull-out of the drawer may be to a relatively slight extent. When, however, the can is full or so nearly full that it should be emptied, then the drawer will be pulled out to the extent, for instance, indicated in dot and dash lines at 16^a in Fig. 2, to cause the can 34 to become disposed as at 34^a. As thus located, the can may be then readily bodily lifted from the bottom wall 17 for emptying.

In either case, incidental to a pull on the handle 43 in the direction of the arrow 47 of Fig. 2, the pivotal connections between the lower ends of the levers 38 and the forwardly bent end portions 30^a, will cause the cover 35 to swing upward as indicated in dot and dash lines in Fig. 2, for being cleared away from the top of the can 34. At the first outward movement of the drawer 16, the lower ends of said levers will be moved toward the dot and dash location 38^a thereby to swing the cover 35 toward the dot and dash location 35^a.

Incidental to a full insertion of the drawer 16, the parts automatically become redisposed as shown in full lines in Fig. 2, thereby reseating the cover 35 on the top of the can 34.

In the modification of the invention shown in Fig. 6, the construction of the storage structure is similar to that described in connection with Figs. 1 to 5, except for a different method of supporting the front portion of the bottom wall 17 of the drawer 16.

The support in this modification of the invention, comprises a pair of rollers 50, one for the front end of each of the tracks 19. The rollers 50 are rotatively supported on pins 51 mounted between the upstanding arms of U-shaped brackets 52. The brackets 52 are in turn fixedly mounted on the top faces of the tracks 19 as by welding, by the application of rivets or in any similar manner.

In other respects, the form of the invention shown in Fig. 6 is similar to that shown in Figs. 1 to 5 and like reference numerals identify like parts in each of the several views.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A combination waste can, enclosure and can lid, comprising a main housing, a slide out drawer therein having a bottom wall on which a waste can may be positioned to remain upright by its own weight on said bottom wall, a can cover, means for permanently pivotally mounting one side of said cover within said housing to be lowered and raised for respectively closing the top of the can and being spaced above such top to permit slide out of the drawer, a linkage connected between the other side of said cover and the inner end of said drawer so that when said drawer is slid out said cover will be raised to space the same above the can top, said housing having a top wall, a rear wall and a pair of side walls and being open at its front and at its bottom, said drawer being L-shaped in side elevation and including said bottom wall and a front wall, and rail type guiding means for said bottom wall carried by said side walls near their bottoms.

2. A combination waste can, enclosure and can lid, comprising a main housing, a slide out drawer therein having a bottom wall on which a waste can may be positioned to remain upright by its own weight on said bottom wall, a can cover, means for permanently pivotally mounting said cover within said housing to be lowered and raised for respectively closing the top of the can and being spaced above such top to permit slide out of the drawer, a linkage connected between the other side of said cover and the inner end of said drawer so that when said drawer is slid out said cover will be raised to space the same above the can top, said housing having a top wall, a rear wall and a pair of side walls and being open at its front end and at its bottom, said drawer being L-shaped in side elevation and including said bottom wall and a front wall, rail-type guiding means for said bottom wall carried by said side walls near their bottoms, said can lid being a plate of greater width than the maximum dimension of the can widthwise of said housing, said pivotal mounting of said cover comprising pin and slot connections between the rear end of the cover and the housing, said pin and slot

3. A combination waste can, enclosure and can lid, comprising a main housing, a slide out drawer therein having a bottom wall on which a waste can may be positioned to remain upright by its own weight on said bottom wall, a can cover, means for permanently pivotally mounting said cover within said housing to be lowered and raised for respectively closing the top of the can and being spaced above such top to permit slide out of the drawer, a handle projected from the front end of the drawer, a linkage connected between the other side of said cover and the inner end of said drawer so that when said drawer is slid out by use of said handle said cover will be raised to space the same above the can top, said housing having a top wall, a rear wall and a pair of side walls and being open at its front end and at its bottom, said drawer being L-shaped in side elevation and including said bottom wall and a front wall, and rail-type guiding means for said bottom wall carried by said side walls near their bottoms, said can lid being a plate of greater width than the maximum dimension of the can widthwise of said housing, said pivotal mounting of said cover comprising pin and slot connections between the rear end of the cover and the housing, said pin and slot connections being adjacent to the opposite limits of the width of the cover, said linkage comprising a pair of levers each close to one of said side walls and pivotally connected at the ends to said drawer and to the front end of the cover.

4. A combination waste can, enclosure and can lid, comprising a main housing, a slide out drawer therein having a bottom wall on which a waste can may be positioned to remain upright by its own weight on said bottom wall, a can cover, means for permanently pivotally mounting one side of said cover within said housing to be lowered and raised for respectively closing the top of the can and being spaced above such top to permit slide out of the drawer, a handle projected from the front end of the drawer, a linkage connected between the other side of said cover and the inner end of said drawer so that when said drawer is slid out by use of said handle said cover will be raised to space the same above the can top, said housing having a top wall, a rear wall and a pair of side walls and being open at its front end and at its bottom, said drawer

being L-shaped in side elevation and including said bottom wall and a front wall, rail-type guiding means for said bottom wall carried by said side walls near their bottoms, said can lid being a plate of greater width than the maximum dimension of the can widthwise of said housing, said pivotal mounting of said cover comprising pin and slot connections between the rear end of the cover and the housing, said pin and slot connections being adjacent to the opposite limits of the width of the cover, said linkage comprising a pair of levers each close to one of said side walls and extended at an angle to the horizontal, the upper end of each lever being pivotally connected to the front end of the cover, and a pivotal mounting for the lower end of each lever, said mountings fixedly carried by the drawer.

5. A combination waste can, enclosure and can lid, comprising a main housing, a slide out drawer therein having a bottom wall on which a waste can may be positioned to remain upright by its own weight on said bottom wall, a can cover, means for permanently pivotally mounting one side of said cover within said housing to be lowered and raised for respectively closing the top of the can and being spaced above such top to permit slide out of the drawer, a handle projected from the front end of the drawer, a linkage connected between the other side of said cover and the inner end of said drawer so that when said drawer is slid out by use of said handle said cover will be raised to space the same above the can top, said housing having a top wall, a rear wall and a pair of side walls and being open at its front end and at its bottom, said drawer being L-shaped in side elevation and including said bottom wall and a front wall, rail-type guiding means for said bottom wall carried by said side walls near their bottoms, said can lid being a plate of greater width than the maximum dimension of the can widthwise of said housing, said pivotal mounting of said cover comprising pin and slot connections between the rear end of the cover and the housing, said pin and slot connections being adjacent to the opposite limits of the width of the cover, said linkage comprising a pair of levers each close to one of said side walls and extended at an angle to the horizontal, the upper end of each lever being pivotally connected to the front end of the cover, and a pivotal mounting for the lower end of each lever, said mountings fixedly carried by the drawer.
